STORM WINDOW

Sam Spector, Shaker Heights, and George J. Teplanszki, Lakewood, Ohio, assignors to Tilt-Type Products, Inc., Cleveland, Ohio, a corporation of Ohio

Application September 7, 1949, Serial No. 114,386

4 Claims. (Cl. 20—52.2)

1

This invention relates to improvements in storm windows and, more particularly, to storm windows of the "self-storing" or other types of windows having sliding sashes which are firmly and tightly sealed when in place but which may be readily removed for cleaning or repairing.

"Self-storing" storm windows are preferably provided with three sliding sashes, two glazed and one screened, carried in a permanently mounted frame. During the winter, one glazed sash is slid to the lower part of the frame and the other to the upper part of the frame, so that the window serves as a storm window. In the summer, the two glazed sashes are carried in the same portion of the frame, usually the upper portion, and the screened sash is moved to screen the remaining opening.

Such self-storing storm windows are by far the most convenient available for quick and effortless changing from storm to screen protection, but are difficult to clean or repair unless the sashes may be removed from the inside of the window. Heretofore the most convenient means of providing removable sashes has been the tiltable frame type shown in our copending application for "Storm Window," Serial No. 85,746, filed April 6, 1949. Such tiltable frames, however, are relatively expensive, though otherwise very satisfactory. Efforts to provide less expensive removable sashes in self-storing windows have heretofore resulted in mechanisms in which the sashes were fitted loosely in the frames without effective sealing. Such sashes rattled badly and were frequently subject to being blown out of the frame.

It is an object of this invention to provide a storm window with sliding sash which is tightly sealed and fitted in a permanently mountable, non-tilting frame, but which may be readily removable for cleaning and repairing. The sash will not rattle in the frame and may be conveniently locked in either the raised or lowered position.

It is another object of our invention to provide means for insuring that the sliding sash fit tightly in the frame, despite variations in manufacturing tolerances or wear over a period of years.

Other objects and advantages of our invention will be apparent from the following specification, claims and drawings, in which:

Figure 1 is an elevation of the outside of a preferred embodiment of a storm window made according to our invention.

Figure 2 is an enlarged side view, broken away, along the line 2—2 of Figure 1.

2

Figure 3 is a still further enlarged detail section of the sill taken along the line 3—3 of Figure 1.

Figure 4 is a detail section enlarged to the scale of Figure 3, taken along the line 4—4 of Figure 1.

Figure 5 is a detail section enlarged to the scale of Figures 3 and 4, taken along line 5—5 of Figure 1.

Figure 6 is an enlarged side elevation, broken 10 away, of a sash.

Figure 7 is a front elevation of the sash shown in Figure 6.

Figure 8 is a detail of the sash pin shown in Figure 6, but with the spacer roll adjusted to a 15 different position, and

Figure 9 is a greatly enlarged corner detail of the inside of the lower left-hand corner of the window shown in Figure 1.

As shown in Figure 1, our preferred embodiment of a window made according to our invention comprises a frame 10 having extruded or rolled metal jamb portions 20 and a lintel portion 30, all preferably of the same section, as shown in Figures 4 and 5, to minimize the inventory of stock required to make various sizes of windows. The jambs 20 are joined by a sill section 40, also preferably of rolled or extruded metal stock as shown in Figure 3. It is to be noted that the jamb sections 20 are provided with scored integral outer mounting fins 12 and the lintel section 30 and sill section 40 are likewise provided with such scored outstanding integral mounting fins 13 and 14, respectively, in order to permit the window to be made in stock sizes, the score-lines 11 permitting the fins to be ripped off in fitting the window to the blind stop of individual window frames which may be warped or otherwise vary from stock dimensions. Such fins are described with greater particularity in our aforesaid copending application Serial No. 85,746, in which they are claimed per se.

As shown in Figure 5, the jamb section 20 is provided with three stepped channels 21, 22, and 23, defined by the channel fins 24, 25, 26, and 27, the outermost fin 24 (with respect to the wall in which the frame is to be mounted) extending the farthest inwardly (toward the center line of the window) and succeeding fins being progressively stepped outwardly (away from the outer line of the window) to provide the stepped arrangement of the channels. The inner ends of the intermediate fins 25 and 26 are provided with enlarged bearing pillow portions 28 and 29, the purpose of which will be described below. It is to be noted that each fin is stepped back from the preceding fin a

distance preferably somewhat larger than the width of the pillow portions 28 and 29.

The lintel section 30, being preferably of the same section as the jamb portion 20, is likewise provided with corresponding stepped channels 31, 32 and 33 defined by fins 34, 35, 36, and 37, the fins 35 and 36 having pillow portions 38 and 39. When the jamb sections 20 and the lintel section 30 are assembled with a mitered joint as shown in Fig. 1, the aforesaid channels coincide to provide continuous stepped channels around the inside of three sides of the frame 10.

The sill section 40, preferably interfitted with the jambs 20 by a butt joint as shown in Figure 1 so that its mounting fin 14 coincides with the jamb fins 12, comprises, as shown in Figure 3, an outwardly slanting drain portion 41 and a channel portion 43 coinciding with the innermost or screen channel 23 of the jamb section 20. The channel 43 is defined by an inner channel fin 41 corresponding with the inner fins 27 and a heavier sealing fin 46, provided with a slanting sealing edge, corresponding to the fin 26.

As shown in Figures 6, 7 and 8, the outer sash 50, slidable in the jamb channels 21 and extending into the lintel channel 31 is comprised of rolled box section stock 51 extending around three sides, i. e. the jambs and lintel, of the sash 50. The box section 51 is provided with an inner glass-receiving channel 52 and an outer corner-clip receiving fin 53. The pane of glass 54 is received and sealed in the channel 52 by means of the extruded rubber glazing channel 55. The clip-receiving rib 53 provides an outer channel between the fin and the box for receiving the compressible sealing strip 56 which seals the space between the sash 50 and the outer jamb fins 24 and the lintel fin 34. It is to be noted that, to provide increased rigidity for the section 51, an inwardly raised portion 57 is provided. (See the sectional showing of the section 51.)

The bottom or sill portion of the sash 50 comprises an extruded channel member 58 in which the pane 54 and rubber glazing channel 55a are received. A corner-clip receiving rib 59, corresponding to the rib 53 of the box section 51, is carried by the sill member 58.

The sash 60 is identical in construction with the sash 50, except that it has laterally larger dimensions to permit it to slide in the jamb channels 22 which, being stepped with respect to the channels 21, are spaced farther apart.

The corners of the lintel and jamb portions of the sashes 50 and 60, all portions being of the box section 51, are mitered. The corners between the sill and jamb portions of the sashes, the members being of different section except for the corresponding fins 53 and 59, are joined for the stepped mitered joint. The fastening with a stepped mitered joint. The fastening means for the corners of the sashes 50 and 60 comprise the channeled right angle corner clips 61 having the channel portions 62 and 63 which are crimped around the fins 53 and 59. In fabricating the clips 61, an outstanding hexagonal boss 64 is drawn in the channel 63 at its corner with the channel 62. These bosses 64 receive and hold frictionally the mounting bearings 65, having an eccentric hexagonal bore 66 fitted on a boss 64. The clips 61 are so mounted on the corners of the sashes 50 and 60 that on each side two bearings 65 extend laterally and are adapted to be received in the jamb channels in which the sashes are slidably mounted.

The screen sash 70 is slidably mounted in the innermost jamb channels 23 and comprises a

frame of rolled box-section stock 71 having a clip receiving fin 72 and an inwardly-opening screen-receiving channel 73 in which the wire screening 74 is held by wedging wire 75. The corners of the screen sash 70 are fastened by means of crimped clips 61, provided with bosses 64 in the same manner as the sashes 50 and 60.

To provide the sashes 50 and 60 with handles for raising and lowering the sashes, the sill members 58 are provided with longitudinal raised portions 67 (raised equally to the portion 51) having a lower slanting edge adapted to seal and mate with the slanting edge of the sill fin 46 (see Fig. 3). Extending lengthwise of the portion 67 is a circular handle-pin receiving channel 68 opening exteriorly through the slot 69. Handles 76 are provided with pins 77 integral with the handle straps 78, the pins 77 extending laterally of the straps 78. The raised portions 67 of the sills 58 are milled off transversely to provide the handle-strap-receiving slot 79-1. The handle strap slots are spaced from the corners of the sashes to provide a central block 67a which limits the sliding movement of the handle straps in the slots 79 and 79-1. Before assembling the frames of the sashes 50 and 60, the handle pins 77 are slid into the channels 68, the straps 78 passing through the slots 69, until the handle straps are free to fall in the slots 79 and 79-1 where the handles are free to swing through a 180° arc. When the sashes are assembled, each frame carries a pair of handles 76 which are slidable in the channel 68 when the handles are perpendicular to the sill 58 but which are held to a limited sliding movement when the handles are swung to a vertical position in the slots 79 and 79-1.

Mounting of the aforesaid glazed sashes 50 and 60 and the screened sash 70 is accomplished by means of the bearing passageways 85, 86, and 87 cut in the lower part of the channel fins 25, 26, and 27, respectively, in each of the jambs 20 (see Fig. 9). To mount the sash 50, for example, the upper pair of bearings 65 on the sash are inserted through the passageway 85 while the sash is held in an approximately horizontal position. With bearing 65 pressed against the outer fins 24 of the jambs 20, the upper bearings 65 are raised in the channel 21, the sash 50 assuming a substantially vertical position as the upper bearings are raised in the channel 21 until the lower pair of bearings 65 are brought opposite the passageways 85 and may be passed therethrough into the channel 21, whereupon the sash 50 may be raised and lowered in the channel 21. To remove the sash 50 for cleaning, adjustment or repairing, the reverse of the above procedure is followed, the lower pair of bearings 65 being first removed through the passageways 85 and the sash then being lowered to a horizontal position so the upper pair of bearings 65 may pass through the passageways 85 and the sash 50 may be removed from the frame 10.

The frame 60 is likewise mounted in its channel 22, its bearings 65 passing through the passageway 86 and the sash 70 is mounted in its channel 23 by passing its bosses 64 through the passageway 87 in the fin 27.

The pillow portions 28 and 29 serve as the ways for the bearings 65 as the sashes 50 and 60 are slid in their respective channels, the sealing strips 56 pressing against the outer fin 24 to seal the sash 50 and the corresponding sealing strip 56 in the sash 60 pressing against the fin 25 to seal that sash. When the sash 50 is in its normal

upper position and the sash 60 is in its normal lower position for services as a storm sash, the sealing strip 56 in the lintel of the sash 60 bears against the raised portion 67 of the sill 58 of the sash 50 to seal the horizontal joint between the sashes 50 and 60.

It is an advantage of this invention that it may be made of continuous lengths of extruded or rolled metal stock which may be cut to desired lengths for making various stock sizes of windows. Consequently, the relatively narrow range of manufacturing tolerances in such stock lengths of constant cross-section insures accurate fit of the window parts in most instances. However, because such manufacturing tolerances do exist and may become cumulative with respect to a given sash in a given frame, the eccentric bores 66 of the bearings 65 permit the effective thickness of the sashes 50 and 60 to be adjusted to accommodate variations in the manufacturing tolerance and to accommodate wear between the bearings and pillows and between the sealing strips and their contacted fins. In Fig. 6 the bearings 65 are shown mounted on the bosses 64 so that the minimum throw of the eccentric bore 66 is effected. This is the normal position of the bearings 65 on the boss 64 when the sashes 50 and 60 are first inserted in the jamb channels 21 and 22. If the sashes are loose in the channels or wear occurs, the sashes are simply removed, the bearings 65 are taken off the bosses 64 and indexed to a position effecting a greater throw, the position of maximum throw being shown in Fig. 8.

To lock the glazed sashes 50 and 60 in either the raised or lowered position, keeper holes 88 are drilled in the pillow portions 28 and 29 to receive the handle pins 77 when the handles 76 are slid outwardly in the slots 79 and 79—1.

Since there is no need to seal the joint between the screen sash 70 and the frame 10, the bearings 65 may be omitted from the bosses 64 on the corner clips of the sash 70. To prevent rattling of the sash 70 and to hold the sash reasonably in either its raised or lowered position, the channel adjacent the fin 72, corresponding to the sealing strip channel in the sashes 50 and 60, may be provided with leaf springs 81 having curved ends which bear against the jamb fins 26 and may fall in suitable detents 82 located on the inner side of the jamb fins 26, as shown in Fig. 4.

Stop fins 83 may be provided in the jamb channel 21 or other suitable means may be employed to prevent the sash 50 from being moved laterally and thereby falling out of the frame 10. The base of the channel 22 and the corner clips 61 prevent any substantial lateral movement of the sashes 60 and 70, respectively.

It is to be understood that features of our above described self-storing storm sash may be incorporated in other windows and, consequently, this invention is not limited in whole or in part to the preferred embodiment disclosed but may be varied by those skilled in the art within the scope of the following claims without departing from the spirit or scope of our invention.

What is claimed is:

1. Window sash having sashes individually removable from the inside of the window compris-

ing a frame defining a sash opening, said frame being comprised of lintel and sill members and a pair of jambs having a plurality of pairs of opposed coplanar channels, said pairs of jamb channels being inwardly offset away from the center of the sash opening so that the outer walls of any given channel extend toward the center of the window farther than the inner wall of that channel, sashes slideable in a pair of said opposite coplanar channels, the lateral dimension between opposite vertically extending sides of a given sash being less than the distance between the inner walls and greater than the distance between the outer walls of the channel in which said sash slides, laterally extending bosses on said vertically extending sides of said sashes, the lateral distance between the ends of opposite bosses on a given sash being greater than the distance between the inner walls of the channel for the sash, and passageways cut in the inner walls of the channels for each of said sashes to permit said bosses to be passed through said inner walls and into the channels in which said sashes are slideable.

2. A window sash as defined in claim 1 in which two of said sashes are glazed and which, when one is in the upper part of said frames and the other in the lower part, can close the sash opening in said frame, and adjustable means on the bosses of said glazed sash to bear against the inner walls of the jamb channels in which said sashes are slideable and to press the outside of said sashes into a weather-sealing relationship with the outer walls of said channels.

3. A storm window sash as defined in claim 2 in which said bosses are polygonal in cross-section and said adjustable means comprise bearing members having eccentric bores mating with said bosses and sealing strips on the outside of said sashes to seal against the outer wall of the jamb channel in which said sashes are slideable.

4. A self-storing storm sash as defined in claim 2, the vertical height of each of said sashes being equal to substantially one-half of the vertical height of the sash opening in said frames.

SAM SPECTOR.
GEORGE J. TEPLANSZKI.
